DYNAMIC SOUND REPRODUCER

Vesper Anderson Schlenker, Orange, N. J.

Application April 5, 1928, Serial No. 267,570

12 Claims. (Cl. 179—115.5)

This invention relates to sound reproducing apparatus for converting electrical currents into sounds corresponding thereto, and more especially to such apparatus in which a sound producing diaphragm is vibrated by the vibrations of an annular coil mounted for movement in an annular air gap.

It is an object of this invention to provide a sound reproducer of the class described which shall operate with high efficiency to produce sound waves which are extremely faithful reproductions of the electric currents which are supplied to the device.

It is a further object of this invention to provide a sound reproducer of the class described in which the power necessary for operation is considerably less than in the known prior art arrangements.

It is still a further object of this invention to provide a loud speaker in which the distortions heretofore inherent in such devices are eliminated or substantially reduced while at the same time the power required for operation is also considerably reduced.

It is still a further object of this invention to provide an arrangement of the movable coil which will permit a substantial reduction in the air gap necessary, thereby permitting a substantial reduction in the driving power utilized without sacrificing volume or quality of reproduction.

Still other objects and advantages of my invention will be apparent from the specification.

The features of novelty which I believe to be characteristic of my invention are set forth with particularity in the appended claims; my invention itself, however, both as to its fundamental principles and as to its particular applications will best be understood by reference to the specification and accompanying drawings, in which:

Figure 1 is a cross section of a sound reproducer according to my invention on lines 1—1 of Figure 4.

Figure 2 is a detail sectional view of the annular movable coil assembly showing the suspension removed.

Figure 3 is a perspective view of the movable coil assembly showing the manner of suspension thereof.

Figure 4 is a front elevation of a sound reproducer according to my invention, partly broken away to show the construction thereof.

Figure 5 is a top plan view of one of the suspension holders.

Figures 6, 7, and 8 are sectional views on lines 6—6, 7—7 and 8—8 of Figure 5 respectively; and

Figure 9 is an exploded sectional view showing the manner of assembly of the driving apparatus according to my invention.

The sound reproducer according to my invention comprises in its essentials, two elements, one 62 being a new and improved form of diaphragm or sound radiator, and the other being a new and improved form of driving motor for vibrating the sound radiator. The diaphragm or sound radiator in itself is shown and claimed in my copending application, Serial Number 262,290, filed March 16, 1928, entitled "Acoustic diaphragm", and is capable of use with other forms of driving motor; similarly, the driving motor shown and claimed herein is capable of use with other forms 65 of diaphragms or sound radiators in addition to that shown. However, I have found that particularly satisfactory results are obtained by the use of the particular sound radiator or diaphragm herein shown with the particular form 70 of driving motor.

It has been suggested in the past for the purpose of vibrating a sound reproducing diaphragm, to utilize an annular coil movable in an annular air gap, the telephonic currents being supplied 75 to the movable coil and a constant uni-directional magnetic flux being maintained across the annular air gap from an inner pole piece of one magnetic potential to an outer pole piece of the opposite magnetic potential. In attempting to 80 make use of such arrangements for driving loud speakers adapted to be operated from the output of a broadcast radio receiver or electric phonograph, considerations of cost have so far required the use of an electro-magnet for establishing the 85 flux in the air gap. While it has been realized for some time that a considerable simplification of apparatus and decrease of cost would result if it were possible to utilize a permanent magnet 90 for providing the magnetic flux through the annular coil, this has so far not been practical because it has been found impossible heretofore to utilize an air gap less than approximately .06" in length, measured from the inner pole piece to the corresponding point on the outer pole piece. 95

With an air gap of such magnitude, the permanent magnet necessary to establish a flux of sufficient value for satisfactory operation with the currents afforded by the usual form of power tubes available in the home, becomes of such size, 100 weight and cost as practically to render its use impossible. In the past, it has not been practical to reduce the size of the air gap because it was impossible to mount the movable coil in a manner 105 which would permit of free axial movement of 110

the magnitudes desired, while preventing lateral motion of the coil or rocking in operation. This lateral motion or rocking results in the coil striking the inner or outer pole piece, particularly on 5 swings of large amplitude, producing characteristic rattling noises and other undesired acoustic effects.

Moreover, even if the lateral motion or wobbling referred to is not sufficient to cause the coil to 10 strike against the pole piece, it serves to deform the diaphragm and to vibrate it in an undesired manner, giving rise to over-emphasis of certain frequencies and partial suppression of others, and otherwise distorting the sound output.

15 In accordance with this invention, I provide a diaphragm which is in itself so arranged that distortions heretofore arising in the known types of diaphragms are eliminated or substantially reduced, and I provide a form of driving 20 motor having an annular coil movable in an annular air gap of considerably smaller size than heretofore utilized.

I also mount or suspend the annular coil in a 25 novel manner, as will be hereinafter pointed out more in detail, so that it is positively restricted to axial movement only and is not permitted to wobble laterally or rock in operation. As a result of such arrangements, I obtain a reproduction 30 of sound of extreme purity and a sound wave which is an extremely faithful copy of the electrical currents supplied to the driving motor: moreover, since the size of the air gap is greatly 35 reduced and since the losses resulting from the undesired motion of the drive are eliminated or substantially reduced, I obtain a considerably increased efficiency of reproduction and am able to substantially reduce the power input necessary for a given sound output.

Referring now more particularly to Figure 1, 40 1 designates generally the core or frame of the magnet having an inner projection 2 terminating in the inner cylindrical pole face 2a. The magnet frame is also provided with an outer portion or skirt 3 in the form of a cup having a pair of outwardly extending flanges 3a and 3b (Fig. 4) enclosing the center pole piece 2, and which is of slightly less length than the center pole piece 2. The magnetic circuit is completed through the outer pole piece 4, having a circular aperture 5 45 surrounding the inner pole piece 2a and defining therewith a cylindrical air gap 5a within which the coil assembly 6 is mounted for axial movement. The surface of the skirt 3 engages the outer pole piece 4 and the corresponding surface 50 of the pole piece 4, are preferably smoothly finished and pressed tightly together so as to minimize the magnetic reluctance of the joint, so that substantially the greater part of the drop in magnetic potential through the magnetic circuit 55 comes within the annular air gap 5.

The annular coil assembly 6 comprises a cylindrical supporting member 8, preferably in the form of a sheet of conducting material, which is not quite closed in order to prevent or minimize 60 its action as a short circuited turn. The form and position of the cylindrical member 8 is maintained by a pair of end rings 9 and 10, the former of which comprises a cylindrical portion 11 and a circular portion 12, while the latter has a cylindrical portion 13 and a circular portion 14. The end ring 9 is preferably directly in contact with the support 8 and is likewise cemented and soldered thereto, whereas the end ring 10 is separated from the support 8 by means of an insulated 70 layer of silk or impregnated fabric 15 sepa-

rating the member 8 and the cylindrical portion 13 of the end ring 10. The coil is wound up of the desired number of turns upon the cylindrical member 8 and will preferably be made in the form of a single layer of suitably insulated wire, one end of which is preferably soldered or otherwise grounded to the support 8: the other end is preferably soldered or otherwise connected to the end ring 10, whereby it will be observed that the end rings 9 and 10 serve as terminals for the annular coil. It will be observed that the longitudinal length of the coil 7 itself is substantially less than the coil assembly: preferably, the coil 7 is made about one third the length of the coil assembly and is positioned longitudinally in the center of the assembly for a purpose which will be described later. The end ring 9, it should be noted, is not put in position until the assembling of the apparatus, as will be hereafter described.

In order to prevent lateral displacement, wobbling or rocking of the coil assembly in operation, it is preferably suspended at each end by a direct acting and positive suspension, the front suspension assembly being designated as 20 and 100 the rear suspension assembly as 21. Each of these suspensions comprises a pair of metallic ribbons disposed at an angle to each other and secured at the center to the coil assembly and at the outer ends to a support.

105 Referring now more particularly to Figure 3, 22 and 23 designate the front suspension ribbons, and 24 and 25 the rear suspension ribbons. The outer ends of the ribbons 22 and 23 are clamped between suspension blocks 26 and 27, while the outer ends of the ribbons 24 and 25 are similarly clamped to the suspension blocks 28 and 29.

110 It is important that the suspension be arranged in a manner to permit maximum vibration of the coil assembly 6 in operation, without stretching the suspension ribbons beyond their elastic limit, and for this reason, the outer supports for the said ribbons are preferably made as far from the center of the coil as is practically possible, in order to provide a minimum change of length 120 as the coil moves in and out: also, I prefer to slightly crimp or corrugate the ribbons transversely or diagonally to their length before assembly, which serves to increase their apparent elasticity. The suspension ribbons are preferably 125 made as thin as possible and relatively wide in order to provide for relatively heavy air damping on the ribbons themselves during the vibration of the coil, for the purpose of preventing the setting up of standing waves in the ribbons, 130 and they are preferably assembled upon the suspension blocks under tension. As a result of this construction, it will be seen that a considerable resistance is interposed both as to lateral movement or wobbling of the coil in the air gap, 135 and also to rocking about its center, while the coil is left substantially free to vibrate axially.

140 It will also be observed with respect to this rocking movement, that if any rocking movement takes place about the center of the movable coil, it will be reduced in the ratio of two to one at the point on the coil in the air gap having the greatest amplitude of rocking motion, and still further reduced at interior points. With this 145 construction I am able to utilize a clearance of only .006" between the coil assembly and the inner pole piece 2a, and only .008" between the coil assembly and the outer pole piece 4. Since the coil assembly is only .014" thick in the air 150

gap, the entire air gap may be no greater than .030" in width.

For the purpose of increasing the air damping on the ribbons, in order to prevent standing waves, I prefer to enclose or partially enclose the ribbons in a dead air chamber so as to obtain a dash-pot action. This may be done by forming the front and rear suspension plates 30a and 30b as shown in Figures 5 to 8 inclusive, in which it will be observed that these plates are provided with a circular cut away opening 31 and a plurality of outwardly extending legs 32, 33, 34 and 35, terminating in flat portions 37, 38, 39 and 40, on which the clamping blocks are mounted. The outer edge 36 is preferably turned inward so as to partially confine the air over a substantial portion of the length of the ribbons. The center pole piece 2a is preferably provided with slots 45 and 46 through which the lower suspension ribbons 24 and 25 pass; and similar slots are also provided in the skirt portion 3 of the magnet. Also, damping may be had by associating felt, or wool, with the ribbons, or by securing paper or the like thereto.

In case it is desired to utilize an electro-magnetic field for driving the annular coil, an energizing winding 14 may be disposed in the space between the inner pole piece 2 and the skirt 3, and for the purpose of facilitating the use of slightly fluctuating direct current in the winding 14, a relatively heavy ring of copper 14a may be placed on the top thereof.

The diaphragm 48 is preferably constructed and arranged in the manner described in my copending application, Serial Number 262,290, filed March 16, 1928, entitled "Acoustic diaphragm", to which reference is had for a full and complete understanding thereof. For the purposes of this application, I believe it sufficient to state that the diaphragm itself is preferably formed out of material having the least possible mass and damping within itself, such for example as aluminum alloys, which have minimum mass and relatively high strength. The diaphragm is formed of metal of the greatest possible thinness, and preferably not more than a few thousandths thick. Satisfactory results have been obtained by the use of such alloys 0.002" thick and having a mass not exceeding 0.03 grams per square centimeter.

The diaphragm is conveniently made in the form of a surface of revolution, such for example as the surface generated by the rotation of a curve represented by $Y = \log_e mx$ about an axis which does not intersect the curve within the generating segment, and the surface so produced will have the general shape of an exponential horn. It is provided with a domed portion 49 at its center, which is reversely curved, and the constants of the generating curve, the axis of revolution, and the segment used, are so chosen that the slope of the diaphragm adjacent the domed portion or the angle between the inner surface of the diaphragm and the plane of its base is approximately 50°, whereas the angle between the outer portion or edge of the diaphragm at the same plane is about 10° to 15°. The constants are likewise so chosen that maximum curvature in the radial direction occurs adjacent the outer edge of the diaphragm. It will be noted that under these conditions, the radial curvature is greatest where the circumferential curvature is smallest, and vice versa.

As a result of the diaphragm construction just described, there is obtained a critically damped

diaphragm having high coupling to the air and relatively low inherent damping. As a result of the structural stiffening given to the diaphragm by the reverse curvature at right angles and as a result of other factors, flexural waves in the material of such a diaphragm have a velocity of propagation which is substantially independent of frequency and approaches that of speed of sound in air, and also the attenuation of the diaphragm is substantially independent of frequency, which operates to decrease phase and amplitude distortion within the diaphragm.

The diaphragm is attached to the coil assembly at the circular junction 50 between the domed portion 49 and an exterior portion of the diaphragm, and for the purpose of providing an air seal to prevent air slippage around its periphery, it may be flexibly connected to a suitable baffle board 52 provided with an inturned flange 53 by means of an annulus or ring 51 of freely flexible and inelastic material, such as leather, plush, or the like, which may be glued to the periphery of the diaphragm and bent over the flange 53, and secured in position by one or more tension members such as string 54. The particular air seal construction utilized forms per se no part of this invention.

In assembling the apparatus thus far described, the front and rear suspensions are preferably assembled independently, the spacing blocks 27 and terminal blocks 61 being positioned upon the front suspension plate 30a on the plane portions 37, 38, 39 and 40, after which the ribbons 22 and 23 are placed in position between the portions 37 and 39, and 38 and 40 respectively. Thereafter, the clamping blocks 26 may be placed over the ribbons, and clamping screws 62 and 63 inserted and drawn tight. In order to insure uniform tension and to avoid excess tension, the ribbons may be stretched to a predetermined tension by means of a spring balance or a weight, after which the clamping bolts may be tightened, and if desired a layer of cement applied at the joint.

After the front and rear suspensions 20 and 21 have been assembled, they will have the form shown in Figure 9. There will also be provided the outer pole piece 4 having the offset end portions 72 and 73 and provided with cut-away portions 70 and 71.

The apparatus may now be assembled as follows: the outer pole piece 4 may be placed upon the magnet 1 and properly centered by means of a suitable centering guage inserted between the center pole piece 2a and the outer pole piece, after which the outer pole piece 4 and the flange portion 3a may be suitably drilled and dowelled, the dowel pins 80 being mounted in the pole piece 4. The pole piece 4 will then be withdrawn. The rear suspension 21 will then be attached to the rear face of the outer pole piece 4.

The coil assembly 6 to which the front end ring 9 has, however, not as yet been secured, will be placed in position in the opening in the pole piece 4, its proper position being determined by means of an outside centering guage or clearance guage, positioned between the coil assembly and the outer pole piece 4. The rear end ring 10 will then be in contact with the rear suspension ribbons 24 and 25, and will be soldered and cemented thereto. The outer centering or clearance guage may now be removed. The front suspension assembly will now be attached to the outer pole piece 4 and the magnet 1 returned to the position determined by the dowel pins previously in-

serted. An inside centering guage will then be preferably inserted between the inner pole face 2a and the inside of the coil holder 8, and the magnet and coil assembly rigidly secured in position by bolts and nuts 83 and 84, after which the front end ring 9 will be positioned upon the coil support 8 and cemented and soldered in place, and thereafter the front suspension ribbons 22 and 23 may be cemented and soldered to the front end ring 9. Thereafter the offset portions 72 and 73 may be secured by means of screws 81 to the baffle plate 52, to which the diaphragm has already been mounted and the diaphragm is cemented to the top end ring 9 at the circular edge 15. 50. The leads supplying the telephonic currents may then be soldered to terminals 60 and 61.

While I have shown and described certain preferred embodiments of my invention, it will be understood that modifications and changes may be made without departing from the spirit and scope of my invention, and also, while I have referred to my apparatus as a sound reproducer, it will be understood that it may also be used for the purpose of converting sound waves into 25. electrical currents.

I claim:

1. In a sound reproducer, in combination, a magnet having an inner pole piece and an outer pole piece surrounding said inner pole piece and defining an annular air gap, an annular coil movable in said air gap, and means for positively maintaining said coil against lateral displacement while permitting free axial movement of said coil, said means comprising a plurality of tensioned ribbons in different planes secured to said coil and to an external support, and disposed at an angle to each other.

2. In a sound reproducer, in combination, a magnet having an inner pole piece and an outer pole piece surrounding said inner pole piece and defining an annular air gap, an annular coil movable in said air gap, and means for positively maintaining said coil against lateral displacement while permitting free axial movement of said coil, said means comprising a plurality of tensioned metal ribbons in different planes secured to said coil and to an external support, the length of said ribbons being sufficiently great with respect to the amplitude of movement of said coil so that the tension in said ribbons is at all times less than the elastic limit of the material of said ribbons, and said ribbons being disposed at an angle to each other.

3. In a sound reproducer, in combination, a magnet having an inner pole piece and an outer pole piece surrounding said inner pole piece, and defining an annular air gap, an annular coil movable in said air gap, and means for positively maintaining said coil against lateral displacement, while permitting free axial movement of said coil, said means comprising a plurality of metal ribbons secured to said coil and to an external support, and disposed at an angle to each other, the length of said ribbons being sufficiently great with respect to the amplitude of movement of said coil so that the tension in said ribbons is at all times less than the elastic limit of the material of said ribbons, and said ribbons being mounted in such manner that the damping thereon prevents the formation of waves in said ribbons during vibration of said coil.

4. In a sound reproducer, in combination, a magnet having an inner pole piece and an outer pole piece surrounding said inner pole piece, and defining an annular air gap, an annular coil mov-

able in said air gap, and means for positively maintaining said coil against lateral displacement, while permitting free axial movement of said coil, said means comprising a plurality of tensioned metal ribbons in different planes secured to said coil and to an external support, and disposed at an angle to each other, the length of said ribbons being sufficiently great with respect to the amplitude of movement of said coil so that the tension in said ribbons is always less than the elastic limit of the material of said ribbons, and said ribbons being crimped in such manner that the developed length thereof exceeds the actual length.

5. In a sound reproducer, in combination, a magnet having an inner pole piece and an outer pole piece surrounding said inner pole piece, and defining an annular air gap, an annular coil movable in said air gap, and means for positively maintaining said coil against lateral displacement while permitting free axial movement of said coil, said means comprising a plurality of tensioned metal ribbons secured to said coil and to an external support at an angle to each other, the length of said ribbons being relatively great with respect to the amplitude of movement of said coil, and means for at least partially confining the air around said ribbons to suppress undesired vibrations thereof.

6. In a sound reproducer, in combination, a magnet having an inner pole piece and an outer pole piece surrounding said inner pole piece, and defining an annular air gap, an annular coil assembly movable in said air gap, and means for positively restricting said coil assembly to plunger action along its axis, comprising a front suspension mounted on the front side of said outer pole piece, and a rear suspension mounted on the rear side of said outer pole piece, each suspension comprising a plurality of tensioned ribbons disposed at an angle to each other, secured to said coil assembly and to an external support.

7. In a sound reproducer, in combination, a magnet having an inner pole piece and an outer pole piece surrounding said inner pole piece and defining an annular air gap, an annular coil assembly movable in said air gap, said assembly comprising a cylindrical form projecting out of said air gap at each end, and means for positively restricting said coil assembly to plunger action along its axis, said means comprising a front suspension mounted on the front side of said outer pole piece, and a rear suspension mounted on the rear side of said outer pole piece, each suspension comprising a plurality of tensioned ribbons disposed at an angle to each other secured to the projecting portion of said coil assembly, and to an external support, and the inner pole piece having openings therein through which the rear suspension ribbons pass.

8. In a sound reproducer, in combination, a magnet having an inner pole piece and an outer pole piece surrounding said inner pole piece and defining an annular air gap, an annular coil assembly movable in said gap, said assembly comprising a winding support, and a winding mounted on said support, and an axially flexible conducting suspension at each end of said assembly, said suspensions forming the supply circuit to said coil.

9. In a sound reproducer, in combination, a magnet having an inner pole piece and an outer pole piece surrounding said inner pole piece and defining an annular air gap, an annular coil assembly movable in said gap, said assembly
